SYSTEM OF MULTIPLE PUMPS.

1,214,300.

Specification of Letters Patent. Patented Jan. 30, 1917.

Application filed November 18, 1910. Serial No. 593,040.

To all whom it may concern:

Be it known that we, PHILIPPE JULES GROUVELLE, EMILE HENRI ARQUEMBOURG, and LÉON JEAN JORET, all of 71 Rue du Moulin Vert, in the city of Paris, Republic of France, engineers, have invented a System of Multiple Pumps, of which the following is a full, clear, and exact description.

Among the various systems of pumps, the rotary, paddle or gear pumps are the only ones which theoretically give an outflow proportional to their number of revolutions. In fact, the piston pumps give, by reason of the inertia of the liquid in motion, outflows which increase more rapidly than the number of revolutions; as regards centrifugal pumps, they do not give any outflow below a certain number of revolutions. But the theoretical superiority of rotary pumps is counterbalanced in practice by the possibility of suppressing the losses due to the necessary play between the members. This play permits of the return backward of a certain portion of the liquid that has been forced back and so these pumps cease to work normally when their speed, decreasing, becomes such that their theoretical outflow for said speed becomes equal to the loss due to the play between the members. There are cases where these pumps must rotate at very variable speeds and where the speed, at certain times, may be very much reduced; and in certain applications it may cause inconvenience if the outflow does not remain proportional to the number of revolutions or even ceases completely.

The present invention has for its purpose to considerably lower the limit of speed for which the outflow of a rotary pump ceases to be proportional to the speed of the latter, so that the reduced speeds at which the pump may be driven remain above the said limit and that the pump gives out proportionally to its speed, in all the conditions to which it is subjected.

The difference between the outflows of two adjacent pumps is chosen in such a manner that, for the determined limit of speed below which the train of pumps will not be lowered practically, this difference is equal to the possible loss; in this way, the train of pumps can cease to proportionally give out only when the speed descends below its lower limit value and, for any greater speed, the normal working of the pump is insured.

Let us suppose, by way of example, there are two consecutive gear pumps p and q of the series, the liquid forced back through p passing at q and being directly sent back by the latter, or through the medium of another or several other pumps up to the final forcing back; it will be understood that if the pump q must force back a volume Q and if, on the other hand, it can let a volume q' escape toward the rear, on the suction side, the preceding pump p must be capable of giving out a volume $P = Q + q'$, for compensating the loss of the pump q . Therefore the theoretical outflows increase by passing from one pump to the adjacent pump toward the suction side, and decrease from the suction side toward the forcing side.

The difference between the outflows may be obtained in any suitable manner; the following means may be indicated by way of example: 1. All the pumps may be identical and have speeds slightly decreasing relatively to one another. 2. The pumps may have different diameters and they may all be actuated at the same speed. 3. The pumps may have the same diameter and the same speed, but the volumes displaced by the penetration of the teeth progressively decrease.

In the accompanying drawing we illustrate three different apparatuses for carrying out our invention. Figure 1 is a sectional and partly diagrammatic view of a pump comprising a casing and two sets of rotary members provided with intermeshing teeth, their peripheries working in the longitudinal passage through which liquid flows. The first set of rotary members, indicated by Z' , z' are rotated at a higher speed than the next or succeeding set, indicated by Y , y the two being driven by a common motor X . The members of each pair are journaled on opposite sides of the passage, into which portions of their peripheries project. All the rotary members are in the same plane. Fig. 2 shows a modification in which the first set of rotary members D' and d' have a greater diameter than the next or succeeding set, indicated by D and d . In other words, it will be understood that D' and D are driven at the same speed, but obviously the peripheries of the larger ones D' and d' move at a faster rate than the peripheries of the succeeding set. Fig. 3 is another modification

in which the first set of rotary members, to wit, E' and e', are driven at the same speed as the succeeding members, F' and f', but the volume of water displaced by the first set is greater by reason of the fact that their teeth are larger or longer.

What we claim is:—

1. The improvement in multiple rotary pumps of the class indicated, comprising a 10 casing having a central passage, a series of pairs of circular rotary members journaled oppositely to each other and on opposite sides of said passage into which they project, all being in the same plane, the members of each pair working in peripheral contact, and a motor which is geared with both pairs, the two members adjacent to the delivery side of the pump operating to produce an outflow less than that of the 20 pump on the suction side, as described.

2. In a multiple rotary pump of the class described, the combination with a casing having a central passage, of two series of pairs of circular rotary members working 25 in peripheral contact and arranged in the same plane with their peripheries projecting into the passage from opposite sides, the members nearest the outflow end of said passage being of lesser diameter than 30 the members of the other pair, and a motor geared with both pairs and rotating them at same speed, as described.

3. A multiple pump of the rotary type indicated, comprising a casing or covering 35 having a central passage, pairs of circular rotary members arranged in said casing, each pair constituting a unit-pump and the members of each pair arranged rotatably opposite each other on opposite sides of 40 said passage and projecting into the latter so that their peripheries work in contact, and means for giving the unit-pumps different peripheral speeds so that the discharge of one is higher than that of the 45 pump it feeds, as described.

4. A multiple rotary pump of the class described, comprising a casing having a central passage, a series of pairs of circular rotary members, each pair constituting a

50 pump unit, the members of each pair rotating oppositely to each other, being arranged on opposite sides of said passage into which they project and working in peripheral contact, all being in the same plane, a motor geared with the pairs of rotary members, 55 and means for giving to the various pump units constituted by said series of rotary members different outflows such that the outflow of each pump unit be greater than that of the pump unit which it feeds according to the losses of the latter.

5. A multiple rotary pump of the class described, comprising a casing having a central passage, a series of pairs of circular rotary members, each pair constituting a 60 pump unit, the members of each pair rotating oppositely to each other, being arranged on opposite sides of said passage into which they project and working in peripheral contact, all being in the same plane, the 65 rotary members constituting two successive pump units having different diameters such that the outflow of each pump unit be greater than that of the pump unit which it feeds according to the losses of the latter, and a motor geared with the pairs of 70 rotary members.

6. A liquid pump of the type indicated, comprising a casing provided with a central passage, two pairs of circular rotary 75 pumps proper, the said pairs arranged in series and the periphery of each pump projecting into said passage and working in peripheral contact with the opposite member of the pair, and means for rotating the 80 several pumps as described, whereby the pump nearest the suction side of the casing has an outflow greater than that of the pump nearest the outflow side.

The foregoing specification of our system 90 of multiple pumps signed by us this 10th day of October, 1910.
